UNITED STATES PATENT OFFICE

HARRIET BACHELEDA, OF MINNEAPOLIS, MINNESOTA

HAIR CURLER

Application filed April 15, 1929. Serial No. 355,276.

This invention relates to improved hair curlers such as are particularly adapted for marcelling and waving the human hair.

The structure herein shown and described is somewhat similar to that seen in an application filed by me under date of October 15, 1927, designated by Serial No. 226,383, and a second application filed by me under date of June 19, 1928, designated by Serial No. 286,400.

Since developing the original structures, I have conceived of added improvements and refinements. The invention shown in the pending cases, as well as the invention shown in this application is characterized by a longitudinally bowed backing member, with which a complementary clamping member is pivotally associated through the medium of a hinged connection at one end, and the opposite ends of these members are constructed for disposition in retained clamping relationship.

In addition, I provide a resilient wire hair curling device which is swingably connected with the hinged end of said clamping members and adapted to be moved into close proximity with respect to the strands of hair.

The principal improvement in this application is the hair binding and curling device or member which is formed from a single length of wire bent upon itself to provide resilient arms which are constructed to be separately and adjustably connected with a keeper on the outer end of the main backing and clamping member.

In the drawings:

Figure 1 is a perspective view of the complete device as constructed in accordance with the present improvement.

Figure 2 is a detail view of the end construction of the swingably mounted curling and hair binding device.

Figure 3 is a perspective view of a connecting link.

Referring now to the drawings by reference numerals, it will be observed that the reference character 8 designates generally the longitudinally bowed main backing and clamping member. This is formed from a single length of wire which is bent upon

itself to provide a pair of spaced parallel arms 9 whose free end portions are bent into hinge eyes 10. The connecting portion 11 is bent at right angles to provide what may be designated as a keeper. The reference character 12 designates a suitable wrapping. Then, too, the reference character 13 designates a slidable clip constituting a keeper.

Cooperable with this is a supplementary clamping member in the form of a longitudinally bowed flat strip 14 the end 15 of which is bent into a hinged knuckle arranged between the eyes 10. These pieces 10 and 15 embrace the bight portion 16 of a connecting link 17. The arms of the link are formed into pivotal eyes 18.

The improvement comprises the device 19. This is formed from a single length of resilient wire, bent upon itself into an elongated loop 20, which is connected with the eyes 18. In addition it is formed into diverging resilient arms 21 terminating in separably connected retaining hooks 22 and 23, respectively. These are bent into interlocking relationship as seen in Figure 2. Adjacent the hook are outstanding bends 24 constituting retaining shoulders. In practice, the free end portions of the arms 21 are extended through the keeper seat 11, and the shoulders 24 are engaged therewith in an obvious manner to hold the arms 21 in binding relationship. The reference character 25 merely designates a protective sleeve which surrounds the arm 21.

The use of the device herein described is substantially the same as the use and operation described in the co-pending applications already mentioned. The strands are placed between the two clamping members 8 and 14 and then the device 19 is connected with the main clamping member to cause the arm 21 to engage and crimp the adjacent portions of the strands of hair.

It is thought that the refinements and improvements herein described serve to simplify the structure and render it more economical and dependent and otherwise efficient in fulfilling the requirements of an implement of this class.

It is thought, too, that by considering the aforesaid application and the preceding de-

scription and drawings, a clear understanding of the invention will be had. Therefore a more lengthy description is regarded unnecessary.

5 Minor changes in shape, size and rearrangement of details may be resorted to in actual practice if desired.

What is claimed is:

1. In a hair curler of the class described, a main backing member formed at one end with hinge eyes and formed at the opposite end with a laterally bent keeper seat, a retaining clip carried by said backing member, a clamping member disposed in substantial parallelism with the backing member and formed at one end with a hinged knuckle disposed between said hinged eyes and having its opposite end arranged for detachable connection with said retaining clip, a substantially U-shaped link having its bight portion passing through said knuckle and said eye, the arms of said links terminating in pivot eyes, and a hair crimping device constructed at one end for hinged connection with said link eyes and having its opposite end constructed for detachable connection with said keeper seat.

2. In a hair curler of the class described, a backing member, a clamping member hingedly connected to one end of the backing member, a link connected to the hinged end of said backing and clamping members, and a hair crimping device formed from a single length of wire bent between its ends to provide an intermediate loop pivotally connected with said link and a pair of resilient normally separable arms, the free end portions of said arms being formed with interlocking hooks and formed adjacent said hooks with retaining shoulders, said backing member being provided with a keeper with which said shoulders are cooperable.

3. As a new article of manufacture, a hair crimping device for use in association with a clamping and backing member of the class described comprising a single length of wire bent upon itself to provide a central elongated pivot loop, and a pair of normally separable spring arms, said arms being provided with protective sleeves and the free end portions being bent to provide a pair of outwardly disposed bent shoulders and the extremities being formed to provide interlocking overlapping hooks.

55 In testimony whereof I affix my signature.
HARRIET BACHLEDA.
